E. VORBROKER,
WINDOW VENTILATOR.
APPLICATION FILED JAN. 30, 1920.

1,360,698.

Patented Nov. 30, 1920.

INVENTOR:

Edmund Vorbroker,
BY John Elias Jones,

ATTORNEY.

UNITED STATES PATENT OFFICE.

EDMUND VORBROKER, OF CINCINNATI, OHIO.

WINDOW-VENTILATOR.

1,360,698.

Specification of Letters Patent. Patented Nov. 30, 1920.

Application filed January 30, 1920. Serial No. 355,035.

To all whom it may concern:

Be it known that I, EDMUND VORBROKER, a citizen of the United States, and a resident of Cincinnati, in the county of Hamilton and State of Ohio, have invented certain new and useful Improvements in Window-Ventilators, of which the following is a specification.

This invention relates to ventilator inserts for use in the space afforded by lowering an upper sash or raising a lower sash, or adjusting both sashes of a window the desired distance to permit the entrance of fresh air from without and the outlet of foul air from within, and its object is to provide a plate or body-portion having one or more orifices therein that are hooded or capped from the outside and screened so as to allow a free circulation of air therethrough but without the passage of foreign material, insects, birds and the like into the chamber where the window is located, the screens being easily applied to and removed from the said capped orifices and the plate or body-portion of the device being provided with stops and outwardly-turned lugs whereby it is properly held in place in the window-frame and the sashes free to slide to and from closing position without hindrance and at will.

In the accompanying sheet of drawings,—
30 Figure 1 is a fragmentary perspective view showing the outer face of a window with my improved telescopic, ventilator filler member or insert in attached position and with the upper sash lowered the desired distance for the ventilator; Fig. 2, an elevation of the inner face of the ventilator showing a shallow perforated metal screen in the vent-orifices thereof; Fig. 3, a view similar to Fig. 2, but with full-size screen fillings in the vent-orifices; Fig. 4, a perspective view of one outer end of the device, showing the orifice protector hood or cap, the outwardly-turned lugs for the fastening-nails and the end stop lugs or extensions; Fig. 5, a vertical section taken on the line 5, 5, of Fig. 2, but with same taken on a larger scale; Fig. 6, a vertical section taken on line 6, 6, of Fig. 2; Fig. 7, a vertical section taken on the line 7, 7, of Fig. 3; and Fig. 8, a diagram of the strip of sheet-metal used in forming the protector hood or cap with short tongues that are adapted to engage slots in the main-plate or body-portion

of the device for bending over on the inner face of such main-plate into fastening position.

9 indicates a main-plate or body-portion made of sheet-metal and provided with an elongated orifice or opening 10 through which the ventilation is effected, a screen 11 being used in the said orifice to duly filter the air passing therethrough.

In the use of my device it is desirable to provide the same in pairs of air-inlet filler members or inserts that are lapped or bent over along their top and bottom edges, as seen at 12 and 13, for longitudinal telescopic-engagement to accommodate various widths of windows. I will describe, however, but one of the filler inserts, as the other is the same except as to the telescopic bent-over upper and lower edges of the metal in the two members, one bent-over edge 12, on one member, (see Figs. 5 and 7,) being a flatly-closed one, and the other bent-over edge 13 on the other member (see Figs. 4 and 6) being an open one, the flatly-lapped edge 12 lying within the openly-folded one 13 for the said telescoping or sliding engagement, and, also, that the outer end of each filler member or insert is provided with stop-lugs 14 and angled fastening-lugs 15 while their inner ends 16 are straight-cut and plain, as best seen in Figs. 2, 3 and 4.

On the outer side of each vent-orifice 10 is provided an overhanging cap or hood 17. The opposite closed ends 17^a and the upper inwardly-extending flange-member 17^b of the cap 17 provide barriers against the accidental displacement lengthwise and upwardly, respectively, of the full-size screen 11 (Fig. 7) from its mounted position in the opening 10. The cap 17 is open only at its mouth or bottom 18 and is made of the same metal as the body-portion 9 and slopes outwardly from the latter, a lip or outwardly-flared 19 being made along the lower edge of the vent-orifice 10, as best shown in Fig. 5, to support the screen 11 at its lower edge and, also, form a suitable wind-break to avoid drafts.

Lugs 20 are cut or turned out from the flange 19, as best shown in Fig. 7, to engage the other side of the lower edge of the screen 11 to hold it in fastened place. The metal is pliable enough to bend the lugs 20 to and

from fastening place, and to turn them outwardly from the face of the body-portion 9 when it is desired to place the screen, or to replace it, especially when it is desired to remove the screen for cleaning it of grease, dirt and other foul or foreign matter that ordinarily collects on it and clogs it in use.

In Figs. 2 and 5 I have shown a perforated sheet-metal screen 11 that is a shallow one and set in an inclined position against the inner face of the cap 17, about mid-height, while in Figs. 3 and 7 I show a wire-mesh screen 11 that is made to fill the entire vent-orifice 10 and to stand perpendicular therein.

The perforated shallow screen of Fig. 5 saves in the use of material and wards off foreign matter the same as the full-size screen of Fig. 7, but I wish to show herein and cover both forms and their adaptability to my simple form of vent-orifice. Screens may, as above stated, be readily removed and replaced, or they may be omitted altogether if desired.

25 The hood or cap may be soldered in place, or it may be made with tongues or lugs 21 that are passed through slots (not shown) in the plate 9 and easily bent over on the inner face of the device into fastening-position, Figs. 2 and 5 both showing how the fastening-tongues are laid over into surface contact.

The stop-lugs 14 are extended from the outer end of each plate 9 and rest flatly against the inner face of the outer run-way strip of the window-frame, and the metal is so thin that it will not prevent the free sliding of the sash to and from closing position without removing the ventilator.

40 As I prefer to use my device in connection with the upper window-sash, for ventilation from the top of the window, the lugs 15 are turned outwardly at right-angles from the sheet-metal, adjacent the said stop-lugs 14, and holes 22 are pierced therein for the fastening nails or the like to attach the

device to the face of said outer run-way strip from the outside of the window-frame.

It is obvious that a single filler member or insert could be used and provided with 50 stop-lugs and fastening-lugs at both ends thereof instead of a telescoping pair of plates, especially for narrow windows, or when but a single vent-orifice is required in small bath-room windows or the like. 55

I claim:—

1. A ventilator device for windows comprising an elongated body-portion having a vent opening therein; a removable screen in said vent opening, one or more lugs projecting upwardly from the lower edge of said vent opening, an overhanging inclined cap extending from the outer side of said opening and registering therewith, stop-lugs projecting beyond the opposite ends of the 65 said body-portion, and lugs projecting outwardly at right-angles from the said opposite ends of the body-portion adjacent the said stop-lugs and adapted to receive fastening-nails that are driven into the window- 70 frame so that the sash may freely pass for opening or closing thereof.

2. A window-ventilator comprising a pair of telescoping plates adapted for longitudinal adjustment, vent openings provided in 75 the plates, pliable detent lugs projecting upwardly from the outwardly-flared lower edge of each of the said vent openings, an overhanging inclined cap extending outwardly from and registering with each of 80 said vent openings, screens detachably fitting within the said vent openings and either partially or wholly filling said vent openings, and outwardly-extending right-angled lugs also provided at the said outer ends of 85 the plates for the reception of fastening nails that are adapted to be driven into the face of the outer strip of the window runways and to permit the sashes to freely slide to and from full closing position.

EDMUND VORBROKER.
